UNITED STATES PATENT OFFICE.

GEORGE WILSON, OF PASADENA, CALIFORNIA.

RAILWAY-RAIL JOINT.

No. 927,305.

Specification of Letters Patent.

Patented July 6, 1909.

Application filed June 25, 1908. Serial No. 448,388.

To all whom it may concern:

Be it known that I, GEORGE WILSON, citizen of the United States, residing at Pasadena, in the county of Los Angeles and 5 State of California, have invented certain new and useful Improvements in Railway-Rail Joints, of which the following is a specification.

My invention relates to railway rail-joints of the joint-chair type; and it has for its object to provide a simple and practical joint constructed with a view of supporting the heads of meeting rails at opposite sides thereof and of affording a continuous support for wheels at one side of the meeting ends of the rails, and this without subjecting the transverse connecting bolts to undue strains.

The nature of the invention and its novelty, utility and practical advantages will be fully understood from the following description and claims when the same are read in connection with the drawings, accompanying and forming part of this specification, 25 in which:

Figure 1 is a perspective view of the joint constituting the best practical embodiment of my invention of which I am aware. Fig. 2 is an enlarged, transverse section of the 30 same. Figs. 3 and 4 are views similar to Fig. 2 illustrating modified constructions of joints hereinafter referred to in detail.

Referring by letter to said drawings and more particularly to Figs. 1 and 2 thereof: 35 A A are the meeting portions of two rails. B is the outside member of my novel joint. C is the inside member of the joint. D D are transverse bolts which I prefer to employ in connecting the members B and C 40 together and to the rails. E, Fig. 2, is one of a plurality of spikes which I employ for fixing the exterior flange of the member B to sleepers or ties, and F F are spikes employed in holding the inside joint member C 45 and the adjacent portion of the outside member B down upon the sleepers or ties. The members B and C are, in the preferred embodiment of my invention, about thirty inches in length, and each is formed in one 50 piece of steel or other material consonant with the purpose of my invention.

As best shown in Fig. 2, the outside joint member B is made up of a body *a* which is 55 of a height to reach from a sleeper or tie to a point flush with the treads of the rails and is provided with a swell *b* interposed be-

tween the bases and heads of the rails, an apertured flange *b* extending laterally outward from the body *a*, a base *c* reaching laterally inward from the lower portion of the body *a* and terminating at its edge remote from the body in a shallow, upwardly extending flange *d*, and one or a plurality of dowels *e* extending laterally from the said edge of the base *c* and designed to serve 65 an important purpose hereinafter set forth. The lower side of the swell *b* on body *a*, the base *c* and the flange *d* are relatively arranged as illustrated, and hence are enabled to snugly receive between them the contiguous portions of the two rails A.

The inner joint member C is shaped to rest on the bases and between the bases and heads of the rails at one side of the webs thereof, and is provided at its outer and 75 lower edge with a depending flange *f* in which is one or a plurality of sockets *g* to receive the aforementioned dowel or dowels of the outside member B.

In the practical installation of my novel 80 joint, the members B and C are arranged as shown relative to the rails, the bolts D are passed through apertures in the said members and through longitudinal slots *h* in the rail webs and are equipped with nuts *i*, the spikes E are driven through the flange *b* and into the sleepers or ties, and the spikes F are driven downward alongside the flange *f* of member C so that their heads rest above the said flange.

With the parts arranged as set forth in the foregoing it will be manifest that the joint members B and C will support the outer portions and the inner portions, respectively, of the heads of the rails, and the outer member B will, by reason of its upper side being flush with the treads of the rails, afford a continuous support for wheels and in that way obviate the objectionable shock and jar incidental to the passage of a wheel 100 from one rail to the other. In this connection I desire it understood that I prefer in practice to slightly incline the end portions of the upper surface of the member B 105 slightly downward as indicated by *j* in Fig. 1, this in order to enable wheels to pass upon the said member without shock or jar.

It will be further manifest from the foregoing that the joint member B is adapted to hold the rails against outward thrust and 110 casual inward movement, and the two members combined with the spikes E and F are

adapted to hold the rails securely down on the sleepers or ties.

The arrangement of the dowel or dowels *e* on member *B* in the socket or sockets *g* of member *C* is materially advantageous because such arrangement enables one member to prevent creeping or casual longitudinal movement of the other member and in that way removes lateral strain from the bolts *D*, and contributes strength and durability to the joint.

In the modified construction shown in Fig. 3, both joint members *B*¹ and *C*¹ are provided with bases which are lettered *c*¹ and *c*², respectively, and the base *c*¹ is provided with one or more studs *e*¹ let into one or more sockets *g*¹ in the base *c*². It will also be seen by reference to Fig. 3 that the member *B*¹ is provided with an exterior, apertured flange *b*² for the passage of one or more spikes *E*¹, and the member *C*¹ is provided with an exterior flange *f*¹ for the engagement of one or more spikes *F*¹.

In the modified construction shown in Fig. 4, the joint member *C*² is provided with a base *c*² which rests under the rails and is flanged as indicated by *b*² and *b*³ to receive spikes *E*², and the member *B*² is provided with one or more dowels *e*² seated in one or more sockets *g*² in said base *c*².

In addition to the practical advantages ascribed to my novel rail joint, it will be noted that the same is simple and inexpensive in construction and is well adapted to withstand the rough usage and exposure to which rail joints are ordinarily subjected.

The constructions herein shown and described are the best practical embodiments of my invention of which I am aware, but it is obvious that in the future practice of the invention such changes in the form, construction and relative arrangement of parts may be made as fairly fall within the scope of my invention as defined in the claims appended.

Having described my invention, what I claim and desire to secure by Letters Patent, is:

1. A rail joint comprising the meeting portions of two rails, joint members ar-

ranged at opposite sides of the rails and between the bases and heads thereof; the outer of said members having its upper side flush with the treads of the rails, and one member having a base extending under the rails, and one member having a dowel and the other member a socket in which the dowel is disposed, means extending through and connecting the rails and the joint members, and means for holding the joint members against upward movement.

2. A rail joint comprising the meeting portions of two rails, an outside joint member having a body resting flush with the treads of the rails, and a swell interposed between the bases and heads of the rails and also having a base extending under the rails and terminating in an upwardly extending flange and a dowel, an inside joint member interposed between the bases and heads of the rails and having a depending flange and a socket therein receiving said dowel, means extending through and connecting the rails and joint members, and means for holding the joint members against upward movement.

3. A rail joint comprising the meeting portions of two rails, joint members arranged at opposite sides of the rails and between the bases and heads thereof; the outer of said members having its upper side flush with the treads of the rails, and one member having a base extending under the rails and beyond the side thereof opposite to that at which the upwardly extending portion of the member is arranged, and one member having, at the side of the rails opposite to that at which said upwardly extending portion is arranged, a dowel, and the other member having a socket receiving said dowel, means extending through and connecting the rails and the joint members, and means for holding the joint members against upward movement.

In testimony whereof I affix my signature in presence of two witnesses.

GEORGE WILSON.
